SWITCH LOCK

Filed July 8, 1929

Inventor:
William J. Butherford

UNITED STATES PATENT OFFICE

WILLIAM J. SUTHERLAND, OF BEDFORD, VIRGINIA

SWITCH LOCK

Application filed July 8, 1929. Serial No. 376,714.

This invention pertains to railway switches and has as its principal object to provide a lock for securing a switch point in place.

A further object of the invention is to provide a lock which will secure a switch point in the closed position, even though the switch stand or its appurtenances which are used for this purpose become inoperative for any reason whatever.

10 A still further object of the invention is to provide a lock consisting of a small number of simple parts which may be readily applied to any of the conventional type switches which are already in service.

15 Figure 1 is a perspective view showing my switch lock applied to a switch point.

Figure 2 is a fragmentary plan view of my switch lock.

Figure 3 is an enlarged longitudinal section through the switch lock proper, the lock being in the closed position, and Figure 4 is an enlarged longitudinal section through the switch lock proper showing the lock in the opened position.

20 Figure 5 is an enlarged sectional view taken on line 5—5 of Figure 2.

In the drawings the stock or running rail 1 is mounted on and secured to the crossties and switch ties 2 in the usual manner. The 25 switch point 3 is shown in the closed position in Figures 1 and 3, and in the open position in Figure 4. The switch stand 4, which may be of any of the conventional types, is shown in Figure 1 for the purpose of indicating its approximate relative position with reference to the switch lock. The connecting rods from the switch stand 4 to the switch point 3, by means of which the switch point is moved from an open to a closed position and vice versa, have been omitted from the drawings for the purpose of more clearly showing the switch lock in position.

25 My switch lock proper consists of casing 5, having a removable cover 6, held in position by means of the screw 7. The casing 5 is recessed at 8 to conform snugly to the contour of the flange of the rail 1. Secured to or made integral with the casing 5 is the plate 9 having through it the openings 10. After 30 the switch lock has been placed in position

with the recessed portion 8 of the casing 5 fitting snugly against the flange of the rail 1, spikes are driven through the openings 10 of the plate 9 into the headblock 11. Thus the switch lock is secured in a fixed position relative to the rail 1. The rail 1 is secured by means of spikes to the headblock 11 as well as to the crossties and switch ties 2.

35 Positioned within the casing 5 is an adjustable carrier 12 having elongated openings 13 in the opposite walls thereof. Disposed within elongated openings 13 are bolts 14 passing from side wall to side wall of the casing 5 and secured therein. Said bolts 14 being smaller in diameter than the width of the openings 13 permit the carrier 12 to be moved transversely relative to the rail 1.

40 Journaled at one end of the carrier 12 in the opposite walls thereof is the stop 15. At the other end of the carrier 12 and made integral with the side walls thereof is the adjusting rod 16, which together with the nuts 17 and lock washers 18 position the carrier 12 within the casing 5.

45 Disposed below the carrier 12 and resting on the bottom of the casing 5 is the plunger 19 which is integral with the rod 20. One end of the plunger 19 engages the bottom of the stop 15. Positioned between the other end of the plunger 19 and the end wall of the 50 casing 5 is the spring 21, enveloping the rod 20.

55 The rod 20 is secured by means of the jaw connection 22 to one end of the rod 23, the other end of said rod 23 being secured to one arm of the bell crank 24. Bell crank 24 is journaled by means of the caps 25 to the plate 26 which is secured to the headblock 11 by means of spikes through the openings 27. The other end of the bell crank 24 is provided with tread pedal 28.

60 The operation of the switch lock is as follows: When the switch point 3 is in the closed position as shown in Figures 1 and 3 the spring 21, which surrounds the rod 20 and which is disposed between the end of the plunger 19 and the end of the casing 5, urges the plunger 19 forward under the stop 15. The plunger 19 engaging the bottom of the stop 15 raises the same to the locking position 65

tion as shown in Figures 1 and 3. In this position the stop 15 engaging switch point 3 holds it securely against the rail 1.

Before the switch can be opened, which opening consists of moving the switch point 3 away from the rail 1 by means of the operating mechanism in the switch stand 4 and the necessary connecting rods, it is necessary to depress the tread pedal 28. The downward movement of the tread pedal imparts a backward movement to the rods 20 and 23 through the bell crank 24. Rod 20 being integral with the plunger 19 imparts a backward movement to the plunger 19, compressing the spring 21. As the plunger 19 moves backward, the stop 15 drops by gravity away from the switch point 3.

As soon as the depression of the tread pedal 28 is sufficient to cause the stop 15 to clear the switch point 3, the switch may be opened by means of the switch stand.

It will be readily seen that when pressure is removed from the tread pedal 28 the plunger 19 being urged forwardly by the spring 21 will exert pressure on the bottom of stop 15, urging it to a position shown in Figure 3. The upward movement of the stop 15, however, is arrested by the switch point 3. As soon as the switch point is closed by means of the switch stand and its appurtenances, the stop 15 is moved to the locking position as shown in Figure 3, and will remain in this position until the plunger 19 is retracted by means of pressure on the tread pedal 28.

When the lock is applied to a switch point, the relative position of the stop 15 with reference to the switch point 3 may be adjusted as desired by means of the adjusting nuts 17. If in the locking position the stop 15 does not securely engage the point 3, holding it against the rail 1, the carrier 12 may be moved transversely by means of the adjusting nuts 17. Thus a fine adjustment of the stop 15 may be obtained relative to the switch point 3.

Normally, a switchman coming to the switch stand 4 for the purpose of opening the switch will first place his foot on the tread pedal 28, depressing same, which in turn will disengage stop 15 from the switch point 3. He can then open the switch by means of the switch stand and its appurtenances.

As long as the switch stand is open, the stop is in a non-locking position as shown in Figure 4. However, as soon as the switch is closed and pressure removed from tread pedal 28, the stop 15 will move into the locking position as shown in Figure 3, securing the switch point 3 against the rail 1.

What I claim is:—

1. A railway switch point lock comprising a casing, an adjustable carrier, a stop journaled in said carrier, a spring actuated plunger positioning said stop against a switch point, and means for retracting said plunger

permitting said stop to move by gravity away from said switch point.

2. A railway switch point lock comprising casing, an adjustable carrier, a stop journaled in said carrier, a plunger, spring means urging said plunger to position said stop in a locking position, and additional means for retracting said plunger, permitting said stop to move by gravity to a non-locking position.

3. A railway switch point lock comprising a casing, an adjustable carrier mounted therein, a stop journaled in one end of said carrier, a plunger engaging the bottom of said stop, spring means urging said plunger to position said stop in a locking position, and additional means for retracting said plunger against said spring means, permitting said stop to move by gravity to a non-locking position.

4. A railway switch point lock comprising a casing, an adjustable carrier, a stop journaled in said carrier, a plunger engaging said stop, spring means urging said plunger to position said stop against a switch point when said switch point has cleared top of said stop, and additional means for retracting said plunger, permitting said stop to move by gravity away from said switch point.

WILLIAM J. SUTHERLAND.
